ADJUSTABLE COUPLING

Benjamin Franklin Giles, Middletown, Ky.

Application March 2, 1955, Serial No. 34,839

Term of patent 14 years

(Cl. D91—3)

Fig. 1.

Fig. 2.

Fig. 3.

Fig. 4.

Fig. 5.

Figure 1 is a top plan view of the adjustable coupling showing the new design;

Figure 2 is a side elevational view of the coupling shown in Figure 1;

Figure 3 is a bottom view of the coupling shown in Figure 1;

Figure 4 is an end view of the coupling shown in Figure 2 looking from left to right; and

Figure 5 is an end view of the coupling shown in Figure 2 looking from right to left.

I claim:

The ornamental design for an adjustable coupling, substantially as shown.
